UNITED STATES PATENT OFFICE.

LUDWIG K. BÖHM, OF HOBOKEN, NEW JERSEY, ASSIGNOR, BY MESNE ASSIGNMENTS, TO THE COMMERCIAL RAILWAY EQUIPMENT COMPANY, OF NEW YORK, N. Y., A CORPORATION OF NEW JERSEY.

WINDOW ATTACHMENT.

SPECIFICATION forming part of Letters Patent No. 758,348, dated April 26, 1904.

Application filed December 9, 1902. Serial No. 134,485. (No model.)

To all whom it may concern:

Be it known that I, LUDWIG K. BÖHM, a citizen of the United States of America, and a resident of Hoboken, in the county of Hudson and State of New Jersey, have invented 5 certain new and useful Improvements in Window Attachments, of which the following is a specification.

This invention has reference to window attachments, and relates particularly to attachments which ventilate the room and keep same at the desired temperature.

The attachment is applied to the bottom rail of the window-sash and to the lower portion 15 of the stop-bead on the window-sill.

A special feature of this invention is that the attachment may be inserted to any window and removed when it is not desired to use same.

20 Another feature of this novel attachment is that no draft is created when same is employed.

The device further is so plain in construction that it can be manufactured very cheaply.

25 The removal of the attachment is very easily effected. It may be done by any one—say a member of the family—because no tools are required for removing same.

The air admitted to the room when the attachment is employed will enter between the meeting-rails of the window. At the same time no air will be admitted below the bottom rail of the window-sash, and the upper half of the window will remain in its usual 35 closed position. When the device is operated, the lower half of the window is raised, admitting cool air between the meeting-rails. In this kind of devices various advantages will be gained for the following reasons: The 40 air naturally enters in an upward direction, and as there is quite a distance between the meeting-rails and the ceiling the air moves in its upward direction until it strikes the ceiling, from whence it gradually descends after 45 having its velocity reduced to some extent by this circuitous course. Thereby the temperature in the room is lowered and the room ventilated without causing any draft, and par-

ticularly the feet of occupants of the room never grow cold. When air is admitted below the bottom rail, then draft is unavoidable. Likewise when air is admitted above the top rail draft is created, because the rushing-in air strikes the ceiling too quickly and is thrown down directly.

50 The invention is illustrated in the accompanying drawings, in which—

Figure 1 is a front elevation of a window with the attachment applied thereto embodying my invention. Fig. 2 is a horizontal section on line 2 2 of Fig. 1. Fig. 3 is a vertical cross-section on line 3 3 of Fig. 2. Fig. 4 is a vertical cross-section showing a modification of the attachment. Fig. 5 represents 55 in vertical cross-section a modified guiding device. Fig. 6 is a horizontal section of the device shown in Fig. 5; and Fig. 7 illustrates in section the side wall of a stock-car, showing the attachment applied thereto. Fig. 8 is a front elevation of the modification shown 60 in cross-section in Fig. 4, wherein a telescoping member is employed in lieu of the single board.

Similar letters of reference denote like parts in all the figures.

75 In the drawings, *a* represents the window, and the attachment applied thereto is designated by the letter *b*. The attachment *b* consists of a board with means to secure same on the stop-bead *d* and the window-sill. There are, further, guiding means on the bottom rail *c* of the window-sash which permit of raising the lower half of the window up on the attachment *b*. The attachment fits between the stop-beads *d* on the sides of the window-frame without being secured thereto, so that the width of the attachment is less than the width of the window-sash, because part of the side rails *e* of the sash is, as usual, covered by the window-frame and stop-bead *d* 80 and the casement *f*. The attachment *b* need not be very thick. However, it must be thick enough to apply therein the means for permitting of sliding the bottom rail up and down thereon.

95 Various means may be employed for secur-

ing the attachment to the stop-bead and the window-sill, and various devices may be used for guiding the bottom rail up on the attachment. In Figs. 1, 3, and 4 the attachment is 5 secured by plain pins *g*, which pass through the stop-bead and the attachment, as is shown in Figs. 3 and 4. The pins are easily inserted and removed, so that the attachment may be easily applied and taken out.

10 The bottom rail-guiding device *h* in Figs. 1 and 2 is shown to consist of angular grooves *i*, contained in the attachment near the ends of same. The groove *i* is wider on the inside, and a similarly-shaped strip *k* of wood 15 or metal secured to the bottom rail slides in the groove *i* when the window is raised or lowered. The strip *k* is permanently secured to the bottom rail *c* and remains there when the attachment is removed. As is shown in 20 Fig. 1, the attachment is of same height as the bottom rail, and necessarily the groove *i* and the strips *k* are of same length.

25 A modification of the guiding device is shown in Fig. 5. It consists of a circular groove *l*, contained in the attachment, and a metal rod *m*, secured to the top portion of the bottom rail *c*.

30 As above stated, the attachment is of same height as the bottom rail of the sash. If it is desired to increase the height of the attachment, then a second board *b'* is employed same as the first, and both are secured to the stop-bead, as is shown in Fig. 4. In this instance the board *b'* adjoining the bottom rail is 35 provided with a tongue *n* on each side near its top ends. Each tongue has an opening which coincides with a like opening in the bottom rail, so that a pin *o* may be inserted in each set of openings. Assuming now that this be 40 done, then the pins *g*, retaining the boards in the stop-bead, are drawn out a little, so as to hold only the board *b*, which adjoins the board *b'*. Upon raising now the lower half of the window the board *b'* adjoining the bottom rail 45 will be raised with same, because it is secured in the described manner to the bottom rail. It may be raised to fully twice the height of the bottom rail, if it is desired to do so.

50 The attachment may be applied to any kind of sliding windows in all kinds of buildings, in railroad-cars, and particularly in stock-cars. In closed stock-cars the animals, particularly horses, suffer a great deal from draft during transportation. Horses easily contract pulmonary diseases and get stiff limbs 55 from the draft during long journeys on the road because it is impossible to keep them in the same atmosphere, and ventilation is absolutely necessary. By the use of my novel attachment no draft is created in the stock-cars, and the animals remain perfectly healthy. Fig. 7 shows a section through the side wall of a stock-car with the attachment applied. A narrow side board *p* is shown in this figure located on the side of the window and reaching

above the meeting-rails up to the top of the window. This is done because the cars are rather low in comparison to the height of the horses, and by the application of such boards on each side of the window no rushing-in air will 70 reach the heads of the horses. The hooks for raising the window necessarily are located on the lower portion of the side rails of the window-sash, as is shown in Fig. 1.

75 It is plainly seen that no devices are necessary for regulating the ingress of the air when my attachment is employed. The lower half of the window may be raised from a trifle to the full height of the bottom rail, thereby regulating the ingress of the air without any 80 special devices.

Having thus described my invention, I claim as new, and desire to secure by Letters Patent—

1. The combination with a window, of a board removably secured to the stop-bead of 85 a window-sill between the stop-beads on the sides of the frame, and means for holding the board in contact with the lower rail of the window-sash, whereby the sash may be raised and air prevented from entering beneath the 90 lower rail.

2. In a device of the class described, the combination with a window, of a board removably secured to the window-sill and having a vertical groove therein, pins in the window-sill 95 engaging the board to hold the latter to the former, and a strip on the bottom rail of the window-sash adapted to engage and slide in the groove in the board, whereby the window-sash may be raised or lowered and air prevented from entering beneath the lower rail 100 of the sash.

3. In a device of the class described, the combination with a window, of a board removably secured to the stop-bead on the window-sill 105 and having two vertical undercut grooves therein, pins mounted in the stop-bead and engaging the board, and strips secured to the bottom rail of the window-sash, said strips engaging the grooves in the board and having 110 their sides diverging outwardly to correspond in shape to the grooves in the board, whereby the board is interlocked with the lower rail of the sash and the latter permitted to be raised or lowered.

4. In a device of the class described, the combination with a window, of means to prevent a draft beneath the lower rail of the sash when the latter is raised comprising a board 120 removably secured to the window-sill and disposed parallel with the sash and having an interlocking sliding engagement with the sash.

5. In a device of the class described, the combination with a window, of means to prevent a draft beneath the lower rail of the sash when the latter is opened, comprising two boards secured to the stop-bead on the window-sill between the stop-beads on the sides of the window-frame, pins mounted in the stop-bead of the window-sill and engaging the 125 130

boards, one of said boards having an interlocking engagement with the lower rail of the window-sash and adapted to be carried thereby when the sash is raised.

- 5 6. The combination with a window having its lower sash provided with dovetail strips extending vertically on the lower rail thereof, of a board mounted on the window-sill contiguous to the lower rail of the sash and provided with dovetail grooves which are slidably engaged by the strips on the sash, tongues on the top of the board having openings therein,

pins fitting in said opening and engaging the sash to lock the board to the sash, a second board in mutual contact with the first-mentioned board, and means to lock the last-mentioned board to the window-sill. 15

Signed at New York, N. Y., this 8th day of December, 1902.

LUDWIG K. BÖHM.
